Des. 203,675
Patented Feb. 8, 1966

203,675

COMBINED TAPE AND CARD PUNCH

Chester J. Abend, Camillus, N.Y., and Jack R. Goodrich,
Martinez, Calif., assignors to SCM Corporation, New
York, N.Y., a corporation of New York

Filed Feb. 2, 1965, Ser. No. 83,668

Term of patent 14 years

(Cl. D26—5)

Fig-1-

Fig-2-

FIG-3-

FIG-4-

FIG-5-

FIG-6-

FIGURE 1 is a front perspective view of a combined tape and card punch, showing our new design;

FIGURE 2 is a front elevation thereof;

FIGURE 3 is a top plan view;

FIGURE 4 is a rear elevation;

FIGURE 5 is a right side elevation; and

FIGURE 6 is a left side elevation thereof.

The essential features of the design reside in the portions shown in solid lines.

We claim:

The ornamental design for a combined tape and card punch, substantially as shown and described.
